UNITED STATES PATENT OFFICE.

RANDOLPH V. WELLER, OF ROCHESTER, NEW YORK.

IRONING MACHINE.

Application filed September 24, 1920. Serial No. 412,508.

To all whom it may concern:

Be it known that I, RANDOLPH V. WELLER, a citizen of the United States, and resident of Rochester, in the county of Monroe 5 and State of New York, have invented certain new and useful Improvements in Ironing Machines, of which the following is a specification.

The present invention relates to ironing machines and more particularly to the type in which there is provided a bed preferably in the form of a roll and a heated or ironing surface cooperating with said bed, an object of this invention being to provide in 10 connection with the ironing surface, a burner which will direct its flame upon the ironing surface when the latter and the bed are in cooperation, but which will direct its flame away from such surface when such parts are out of cooperation. Another object of 15 this invention is to provide an actuating means for effecting a relative movement between the bed and the ironing surface, such means being of simple construction and permitting the machine to adapt itself to goods 20 of different thicknesses. A further object of the invention is to provide an actuating means in which the operating member thereof, when operating at one time, will effect cooperation between the iron and the bed and when actuated the next time will 25 effect a separation of these two parts.

To these and other ends, the invention consists of certain parts and combinations 30 of parts, all of which will be hereinafter described, the novel features being pointed out in the appended claims.

In the drawings:

Fig. 1 is a front view of an ironing machine constructed in accordance with this 40 invention;

Fig. 2 is an end view;

Fig. 3 is an end view of the opposite end of the machine;

Fig. 4 is a detail view of a portion of the actuating mechanism;

Fig. 5 is a sectional view through a portion of the actuating mechanism shown in Fig. 4;

Fig. 6 is a view of the actuating mechanism similar to that shown in Fig. 4 in which the parts are shown in the positions which they occupy when the iron is in co-operation with the bed;

Fig. 7 is a detail view showing the man-

ner in which the detent operates to hold the iron in cooperation with the bed;

Fig. 8 is a sectional view through the bed and the iron, showing the burner adjusted to direct the flame away from the iron; 60

Fig. 9 is a detail sectional view similar to Fig. 8, showing the burner adjusted to direct its flame on the iron; and

Fig. 10 is a longitudinal sectional view showing the burner in its position on the iron. 65

Referring more particularly to the drawings, 1 indicates the bed on which the material is ironed. This bed is, in this instance, in the form of a wooden drum with 70 a padded covering rotatably mounted at its end in end pieces 2 which have their opposed faces grooved to receive the ends of a base 3, the ends of the end pieces projecting below the base. Cross pieces 3^a are secured by screws to the under side of the base, and screws or fastening devices pass through the end pieces and into the base and the cross pieces. The inner faces of the cross pieces are beveled or inclined so as to 75 form abutments for the supporting legs 4 which are hinged to the base 3 at 5 so as to fold inwardly, the upper ends of the legs also abutting the under side of the base. The drum 1 may be driven in any suitable 80 manner. In this instance, on one end of its shaft, a gear 6 is arranged with which meshes a pinion 7 on the countershaft 8, said countershaft also carrying a large 85 worm wheel 9 meshing with a worm 10 on the shaft of the motor 11. The motor is supported on a bracket 12 which is detachably held to one of the side pieces by bolts 13. By removing the motor and the casing 14 which carries the gears 7 and 9 with the 90 countershaft 8, the gear 6 may be exposed 95 for driving through other means.

The iron or heated surface is, in this instance, in the form of a cast metal plate 15 curved to conform to the periphery of the bed and supported at opposite ends by arms 16 which are pivoted at 17 to the side pieces 2. The iron is preferably heated by a burner tube 18 extending parallel with the axis of the bed 1 and having a longitudinal 100 series of openings 19 from which the flame plays. This burner tube is preferably journaled in the arm 16 in order that the openings 19 may be turned to direct the flame either upon the ironing surface 15 as shown 110

2
in Fig. 9 or away from said surface as shown in Fig. 8. A hood 18^a may be secured to the arms 16 to provide a chamber in rear of the iron 15 so as to house the 5 burner tube 18. This hood is open at its bottom and is provided with openings 18^b near its top so that proper air supply to the burner is insured.

The movement between the bed and the 10 iron for effecting cooperation between them is produced by an actuating mechanism of novel construction. This actuating mechanism consists, in this instance, of two flexible and resilient straps 20, one end of each 15 of which is anchored at 21 to a fixed part such as the side frames 2 of the machine, while the other end is spirally wound about the burner tube 18, the two straps being arranged at opposite ends of the burner tube 20 beyond the ends of the iron. With the turning of the tube 18, which acts as a shaft, the straps 20 will be wound on such tube and will draw the iron toward the bed 1. The iron under its own weight will 25 fall away from the bed 1 when the burner tube 18 is released and this unwinds the straps 20 from the burner tube. For turning the burner tube, the latter is deflected laterally at 23 to provide an arm through 30 which the fuel is fed to the burner tube by a tube 24, air openings 25 being provided at the end of the arm about the fuel tube. This arm 23 connects with a member 26 in this instance mounted to turn in a complete 35 circle about an axis 27. The connection between the arm 23 and the member 26 is preferably resilient, being in the form of a helical spring 28 anchored at 29 to the arm and at 30 to the member 26, the point 40 30 being eccentric to the axis of the member 26. The member 26 preferably has two arms of different lengths, the connection 28 being secured to the short arm, while the opposite arm is adapted to cooperate with 45 a stop or detent 31 situated out of the path of the short arm. This stop or detent 31 is pivoted at 32 within a casing 33 which also houses the member 26. A spring 34 acts on the stop or detent to hold it in the 50 plane of operation of the long arm of the member 26.

A mechanism is provided for turning the member 26 in a direction so that it will ride over the detent 31 and the detent is 55 situated at such a point that when the short arm is lowermost and the spring pulls on said short arm at a slight angle to the vertical, the long arm of the member 26 will be held against the detent, thus holding 60 the iron in cooperation with the rotary bed. This position of the parts is shown in Fig. 6 where the dotted line indicates the direction of the pull of the spring 28. Movement of the member 26 may be effected 65 through an oscillatory member 35 in the

form of a drum rotatable on the shaft 27 and carrying a detent 36 which is pivoted at 37 and is acted upon by a spring 38. On one operation of the oscillatory member 35, the detent 36 will cooperate with 70 the short arm of the member 26 and shift said member slightly beyond the swinging end of the detent 31, the movement of the member 35 being limited by a stop 38^a thereon cooperating with the abutment 39. After this position of the member 26 is reached, the member 35 returns to its original position under the action of a spring 40 preferably of volute form anchored at 41 to the housing 33 and at 42 to the member 35. 80 On the next operation of the member 35, the detent 36 will engage the long arm of said member 26 and shift said member to such a point that the spring 28 will act on the member 26 independently of the 85 member 35 and permit said member 26 to return to its normal position, where the iron will be out of cooperation with the bed 1. Movement of the member 35 may be effected by a flexible connection 43 anchored at 44 to the drum of the member 35 and partially wound about said drum. The lower end of this connection is secured at 45 to an operating member in the form of a foot lever 46 pivoted at 47 to one of the supports 4, 90 a brace 48 being anchored at 49 to the foot lever and at 50 to the support 4 in order to prevent sidewise swinging of the foot lever 46.

In the use of the machine, the iron having 100 been heated through the burner 18, the motor 11 is started. The goods are then placed upon the uppermost portion of the bed so as to project between the bed and the iron. The operating treadle 46 is then depressed to bring the iron into cooperation with the bed and to turn the burner tube so that the flame 19 plays on the iron. After the goods have been ironed, the 105 treadle 46 is again depressed which permits the iron to move away from the bed 1 under its own weight.

From the foregoing it will be seen that 110 there has been provided a burner which is movable to direct the flame upon the iron while the latter is in cooperation with the bed and to direct the flame off the iron while there is no cooperation between the iron and the bed. In this way, the overheating of the iron is prevented, due to the 115 fact that even though the machine is not in use for some time, the flame will not play on the iron except that the iron be in cooperation with the bed. The actuating mechanism for effecting the relative 120 movement between the iron and the bed is of simple construction. It yields to permit goods of different thicknesses to be held between the bed and the iron, this yielding being permitted after the iron and bed 125 130

have been brought into cooperation. This construction is inexpensive to manufacture and its operation is simple.

What I claim as my invention and desire 5 to secure by Letters Patent is:

1. An ironing machine comprising a bed, an iron, a movable burner for heating the iron, and mechanism for effecting a relative movement between the bed and the iron 10 connected to the burner for effecting the movement of the latter to cause its flame to play on the iron while the iron and the bed are in cooperation, and to play away from the iron when said parts are out of 15 cooperation.
2. An ironing machine comprising a bed, a burner tube rotatable on the iron about an axis extending longitudinally of the tube and having openings which in one position 20 will play upon the iron and in another position will play away from the iron, and means connected with said rotary burner for effecting a movement of the iron toward the bed when the burner is shifted to play on 25 the iron.
3. An ironing machine comprising a bed, an iron, an operating member rotatably mounted on one of said parts, and a strap secured at one end to and wound about the 30 rotary member and secured at its other end to a fixed part so that a relative movement between the iron and the bed is effected on the turning of said member.
4. An ironing machine comprising a bed, 35 an iron movable toward and from the bed, a rotary operating member mounted on the iron, and a strap secured at one end to and wound about the rotary member and connected with a fixed part.
5. An ironing machine comprising a bed, 40 an iron movable toward and from the bed, a burner mounted to turn on said iron, and a strap connected with said burner to be wound with the turning of the burner and having its other end secured to a fixed part.
6. An ironing machine comprising a 45 frame, a bed rotatably mounted on said frame, an iron pivotally mounted on the frame to cooperate with the bed, a burner rotatable on said iron about an axis extending parallel with the axis of rotation of the bed, and a strap having one end secured to the frame and its other end secured to the burner to be wound when the latter is turned.
7. An ironing machine comprising a 55 frame, a bed rotatably mounted on the frame, an iron pivotally mounted on the frame to cooperate with the bed, a burner tube mounted to turn on the iron and having openings adapted to play upon the iron when the burner tube is moved in one direction and to play away from the iron when the burner tube is moved in the other direction, and a strap secured to the frame and
8. An ironing machine comprising a bed, 60 an iron, and mechanism for effecting a relative movement between them comprising a member rotatable in a complete circle, and having two positions, one for holding the parts in cooperation and the other for permitting the separation of said parts, a detent mounted on a part fixed relatively to the rotary part for retaining the rotary member in the position where it holds the parts in cooperation, and mechanism for effecting 65 the movement of said rotary member, to one position in cooperation with the detent, and then to the other position out of cooperation with said detent, said mechanism comprising an oscillatory member engaging the rotary member when moved in one direction and turning in the other direction free of 70 said rotary member.
9. An ironing machine comprising a bed, 75 an iron, and mechanism for effecting a relative movement between them comprising a member rotatable in a complete circle and having two positions, one in which it holds the iron and the bed in cooperation and the other of which it permits the separation of 80 said parts, a resilient connection between one of the first two named parts and a point on the rotary member eccentric to the axis of the latter and an oscillatory member movable in one direction to engage and turn 85 the rotary member and in the other direction, free of said rotary member.
10. An ironing machine comprising a bed, 90 an iron, and mechanism for effecting a relative movement between them comprising a member rotatable in a complete circle and having two positions, one in which it holds the iron and the bed in cooperation and the other of which it permits the separation of 95 said parts, a resilient connection between one of the first two named parts and a point on the rotary member eccentric to the axis of the latter and an oscillatory member movable in one direction to engage and turn 100 the rotary member and in the other direction, free of said rotary member.
11. An ironing machine comprising a bed, 105 an iron, and mechanism for effecting cooperation between the bed and the iron comprising a rotary member having two positions, one of which causes cooperation between the bed and the iron and the other of which permits the separation between 110 such parts, a resilient connection between one of the first two named parts and a point on the member eccentric to the axis of the latter, an oscillatory member movable in one direction to shift the rotary member and in the other direction free of said rotary member, an operating member for shifting the oscillatory member in the direction in which it shifts the rotary member, and a spring for moving the oscillatory member in the other direction.
12. An ironing machine comprising a bed, 115 an iron, and mechanism for effecting cooperation between the bed and the iron, said mechanism embodying a member rotatable in a complete circle having two 120 positions, one for causing the cooperation between the iron and the bed, and the other for permitting a separation of said parts, a detent for holding said member in the first mentioned position, an oscillatory 125 member
13. An ironing machine comprising a bed, 130 an iron, and mechanism for effecting cooperation between the bed and the iron, said mechanism embodying a member rotatable in a complete circle having two positions, one for causing the cooperation between the iron and the bed, and the other for permitting a separation of said parts, a detent for holding said member in the first mentioned position, an oscillatory member

member adapted to cooperate with said rotary member to shift the latter when moved in one direction and to move free of said rotary member when moved in the other 5 direction, a treadle having a flexible connection with said oscillatory member to move the latter in a direction in which it shifts the rotary member, and a spring for moving said oscillatory member in the opposite direction.

12. An ironing machine comprising a rotary bed, an iron movable toward and from the bed, a shaft mounted to turn on the iron, a connection between said shaft 13 and a fixed part for effecting the movement of the iron toward and from the bed, a member rotatable in a complete circle and having a resilient connection with said shaft to turn the latter, said rotary member 20 having two positions, one of which effects cooperation between the iron and the bed and the other of which permits the separa-

tion of such parts, a detent for holding the rotary member in the first named position, said detent being so situated that the resilient connection holds the rotary member in cooperation with the detent, and means for effecting the movement of the rotary member in a complete circle.

25

13. An ironing bed having a padded covering, a shoe conforming to the surface of the bed, a heating means for the shoe, and means for reducing the intensity of the heat upon said shoe as the shoe moves away from the bed.

30

14. In an ironing machine, an ironing roll, a movable ironing member cooperating therewith, a gas burner located within said ironing member, and means controlled by the movement of said ironing member for moving said burner to vary the heating effect of its flame upon the working wall of said member.

35

RANDOLPH V. WELLER.
